UNITED STATES PATENT OFFICE.

HENRY C. HOOK, OF BRIDGEPORT, CONNECTICUT, ASSIGNOR TO INTERNATIONAL FUEL SERVICE CORPORATION, OF BRIDGEPORT, CONNECTICUT.

UNDERGRATE DRAFT BLOWER.

Application filed June 13, 1927. Serial No. 198,518.

My invention relates to a fan blower, and more particularly to a fan blower adapted to be used as an under grate draft blower for a heating system.

5 The fans and motors used for creating a draft in a heating system are usually mounted closely adjacent the ash pit or connected to the fire box under the grate where they are in contact with dust from the furnace, which 10 is largely composed of carbon. The dust works into the motor and not only wears out the bearings rapidly, but being carbon, in working in between the field and the rotor is quite apt to produce a short circuit and cause 15 the motor to burn out. As an object of my invention, I contemplate an arrangement of the motor and the fan blower in which dust is prevented from penetrating the motor, and the wear and danger caused thereby eliminated.

20 There is considerable danger in using motors closely adjacent the ash pit of a furnace or heater from water accumulating in the basement in which the heater is placed. This 25 danger is not only from water directly penetrating the motor, but also if the motor is near a damp or wet basement floor, the vapor arising from the floor is apt to condense in and on the motor. As an additional object 30 of my invention, I contemplate a mounting for the motor and fan wherein they are carried in an elevated position out of reach of any water which may accumulate around the heater.

35 In order that the motor may not become over-heated when in use, it is generally considered necessary to ventilate the motor housing. As a further object of my invention, I contemplate a means for ventilating a motor 40 housing when used with a fan blower in which there is no danger of dust or other foreign matter entering the housing and damaging the parts of the motor.

45 To these and other ends, the invention consists in the novel features and combination of parts to be hereinafter described and claimed.

In the drawings,

50 Fig. 1 is a side view, partially in section, of a furnace showing a preferred embodiment of my under grate draft blower mounted thereon;

Fig. 2 is a plan view of the motor and fan casing with the screen removed; and

Fig. 3 is an elevational view, in section, showing the interior arrangement of the motor and fan casing. 55

Referring to the drawings in which I have shown a preferred embodiment of my invention, the reference numeral 4 indicates a furnace having at the bottom thereof an ash pit 5, and secured at the rear of the ash pit around an opening formed therein is a pipe 6, having mounted thereon an elbow 7 with my draft blower, generally designated by the reference numeral 8, mounted on the upper end thereof. The draft blower consists of a fan casing 9 having mounted thereon an electric motor 10, which is preferably a universal variable speed motor adapted for either alternating or direct current. The motor 10 consists of a two-part casing 11 and 12, secured together in any suitable manner, and on an intermediate portion of part 12 and extending radially therefrom are legs 13, 14 and 15, secured on the upper end of the casing 8 by means of cap screws 16, 17 and 18. Within the motor casing part 11 is a field magnet 19, surrounding an armature 20, mounted on a shaft 21, supported in bearings 22 and 23, mounted in the lower end of part 12 and the upper end of part 11, respectively. On the shaft 21 is a commutator 24 and arranged in the motor casing 11, opposite one another, are brushes 25 and 26, each in contact with the commutator 24. 85

The fan casing 9 has in the interior thereof in an intermediate position a throat 27, and above the throat the wall of the casing tapers outwardly, as shown at 28. Mounted on the lower end of shaft 21 is a fan 29, 90 having outwardly and upwardly extending blades 30, the outer ends of which are opposite the throat 27. The motor casing part 12 is spaced from the upper end of the tapered wall 28, and has an inwardly and downwardly tapering wall spaced inwardly from the fan casing and forming with the wall 28 an intake for the fan 29. Below the fan 29 and formed integrally with the casing 9 are a series of radial fins 32 for a purpose to be hereinafter described. 100

Mounted on the upper surface 33 of the casing 9 is a screen 34 having its lower edge 35 resting on the upper edge 33 of the casing 9, the upper end of the screen 34 closely embracing the motor 10. A series of wedge

members 36 are carried within the screen 34, each of the wedges having one of its ends in contact with a portion of the inner wall of the screen at the lower end thereof, and 5 its upper end in contact with a portion of the motor wall which is tapered inwardly slightly at this point, as indicated by the reference numeral 37. The motor casing 10, below the field 19, is connected to the intake of the fan 10 chamber by a series of openings 38.

On the top of the motor 10 in the part 11, covering the bearing 23, and rendering the motor casing dust-tight at this point, is a hollow cap 39, having a plug 40 in the upper 15 portion thereof. In the lower end of motor casing part 12, and above the bearing 22, is a grease or oil chamber 41, having a cover 42, and connected to the chamber 41, by means of a pipe 43, is a grease or oil cup 44. The 20 brushes 25 are carried in tubes 45, mounted in bushings 46, fixed in the motor casing, and are urged against the commutator 24 by springs 47, the outer ends of which are supported by caps 48 which, in conjunction with 25 bushings 46, render the motor casing dust-tight. Below the bearings 22 and 23 are grease or oil traps 49 and 50 which prevent the entry of oil into the motor 10 and the fan 10 casing 9, respectively.

30 In operation, it will be understood that electric current, either alternating or direct, may be supplied to the motor and, if desired, may be controlled by a thermostatically operated switch inserted in the heater and wired 35 in series with the motor. Upon rotation of the shaft 21, and the fan 29 carried thereon, air is drawn through the screen 34 downwardly between the walls of the fan casing 9 and the tapered surface of the motor casing part 10 12 by the fan 29. The air discharged by the fan passes between the fins 32 arranged therebelow, which prevent rotary movement of the air passing through the draft blower. All of the parts of the motor casing above the screen 15 34 are air and dust-tight, and no dust can penetrate the motor above this point. The openings 38 in the lower part of the motor casing permit the casing to be ventilated and cooled. Since the air passing to the rotary 20 fan is drawn by these openings, there is a tendency for the air to entrain other air from the motor casing and prevent dust from entering through the openings in the latter. In addition, these openings being carried in 25 an under surface of the motor casing, there is no tendency for dust to settle therein while the motor is idle. By means of the wedges 36, the screen may be detachably secured on the fan housing, the tapered portion 37 of 30 the motor casing 10 cooperating with the upper edge of the wedges to secure them tightly in place. The provision of an upwardly extending connection between the draft blower and the ash pit permits the motor to be 35 carried in an elevated position where it may

not readily come in contact with any water accumulating in the basement and is not likely to be endangered by an accidental blow.

While I have shown and described a preferred embodiment of my invention, it will be understood that the same is not to be limited to all the details shown but is capable of modification and variation within the spirit of the invention and the scope of the appended claims.

What I claim is:—

1. In a draft blower, a vertical fan casing, a vertical motor mounted on said casing, and having a rotary shaft extending downwardly 80 into said fan casing, a fan on said shaft and within said casing, a screen between said motor and said casing, said motor being partly carried within but spaced from said casing to provide an intake for said fan, the motor casing above said screen being dust-tight, and said motor casing being provided with openings therein below said screen and within said fan casing.

2. In a draft blower, a vertical fan casing, 90 a vertical motor mounted on said casing, said motor having a casing and a rotary shaft extending downwardly into said fan casing, a fan on said shaft, said motor casing having an outwardly and upwardly tapering side 95 wall above said fan, said motor casing having its lower end received within the casing, and said motor casings being provided with openings leading from the interior of said fan casing into the interior of said motor.

3. In a draft blower, a vertical fan casing, a vertical motor mounted on said casing and having a casing and a rotary shaft extending downwardly into said fan casing, a fan on said shaft, said motor casing having an outwardly and upwardly tapering side wall above said fan, said motor casing having its lower end received within the casing, said lower end having an upwardly and outwardly tapering wall, and said motor casing being 105 provided with openings in said tapering lower end leading from the interior of said fan casing into said motor casing, and a screen between the upper end of said fan casing, and said motor casing, said screen being detachably secured on said fan casing.

4. In a draft blower, a vertical fan casing and a vertical motor supported on the upper edge of the fan casing and extending partly into said casing, the exterior walls of said motor being spaced from the interior walls of the fan casing, and the motor wall being provided with ventilating openings in an under portion thereof, the motor above said openings being dust-tight.

5. In a draft blower, a vertical fan casing and a vertical motor supported on the upper edge of the fan casing and extending partly into said casing, the exterior walls of said motor being spaced from the interior walls 130

of the fan casing, and ventilating openings in an under portion of the motor wall and within said fan casing, the motor above said openings being dust-tight.

- 5 6. In a draft blower, a vertical fan casing and a vertical electric motor supported on the upper edge thereof, said motor including a casing and a field and armature within said casing, the exterior walls of said motor being spaced from the interior walls of the fan casing, and the walls of said motor being provided with ventilating openings in an under portion thereof, said field and armature being carried in said motor casing at an elevated position above said ventilating open-

ings, and said motor casing being dust-tight above said openings.

7. In a draft blower, a fan casing, a motor mounted partly in and spaced from the walls of said casing at one end thereof, said casing being provided with inwardly extending lugs at said end, and said motor being provided with radially extending legs mounted on said lugs, and a screen mounted on the end of the fan casing, said motor extending through said screen and the extending part of the motor casing being dust-tight. 20 25

In witness whereof, I have hereunto set my hand this 4th day of June, 1927.

HENRY C. HOOK.
